UNITED STATES PATENT OFFICE

JOHN EDWARD GLOEKLER, OF PITTSBURGH, PENNSYLVANIA

REFRIGERATOR DISPLAY CASE

Application filed November 3, 1928. Serial No. 316,955.

The object which I have in view is to improve and strengthen the construction of refrigerator display cases.

One of the novel features of my invention is the improved means for supporting the top closure of the case without the employment of interior supports or posts.

Another feature is the floor structure of the case.

10 Another feature is the novel top closure structure of the case.

Other novel features of construction, and also of arrangement of parts will appear from the following description.

15 In the accompanying drawings, Fig. 1 is a sectional perspective of a refrigerator display case embodying my present invention; Fig. 2 is a cross sectional view showing one of the truss braces and its relation to associated parts; Fig. 3 is a reduced perspective showing one of the front corners of the case; Fig. 4 is a broken section taken on the line IV—

IV in Fig. 3 and on enlarged scale; Fig. 5 is an inverted plan view of the corner cap plate also shown in Figs. 3 and 4; Fig. 6 is a broken side elevation of the corner reinforcing guard; Fig. 7 is a section taken along the line VII—VII in Fig. 6; Fig. 8 is a plan view of the type of cap plate employed with

20 the intermediate reinforcing guards; Fig. 9 is a sectional view taken along and looking upwardly from the line IX—IX in Fig. 2, and Fig. 10 is a detail showing the corner brace in plan.

25 The following is a detailed description of the drawings.

1 is a horizontal floor supported from below by the base 2 of the case. At the front and rear of the floor are secured the superimposed sills 3 and 4, said sills being connected together at spaced intervals by the transversely disposed joist 5. The tops of the joist 5 and the rear sill 4 are in the same plane but that of the front sill 3 is on a higher plane. The spaces between the sills and joist are filled with cork or other heat-insulating material 6.

30 7 is a cleat mounted on the joist 5 parallel with but spaced in front of the rear sill 4.

50 The top surface of the cleat is in the same

horizontal plane as the top surface of the sill 3. A sheet 8 of galvanized metal covers the sills, joist, cleat and insulation, being bent to conform to the top surfaces of the same, and thus preventing the downward entrance 55 of moisture.

9 represents the opalescent glass or marble slabs which are supported by the front sill 3 and the cleat 7, and which forms the load-bearing surface of the case.

60 Difficulty is experienced when these slabs are laid on a continuous surface or plane, as the slabs are usually not perfectly flat and their tendency is to crack. By providing elevated supports for the slabs at front and rear 65 I prevent cracking, and I also obtain an air space or chamber beneath the slabs which has a material insulating value.

A represents the transversely disposed, 70 metal truss-frames which are positioned at proper intervals to support the super-structure of the case.

Said frames are provided with inturned 75 feet 10 which fit down into notches 10^a in, and are attached to the front and rear sills. The front of each frame A is composed of a vertical portion 11 from whose upper end extends rearwardly the horizontal portion 12, merging into the rearwardly and downwardly inclined portion 13 which in turn 80 merges into the rearwardly extending and horizontal portion 14 whose rear end merges into the rear, vertical portions 15 which extend down in the rear of the sill 4. The floor slabs 9 are notched to provide clearance 85 for the frames A, and their front edges are flush with the fronts of the frames.

16 is a front plate, which may be of wood 90 and which extends up above the sill 3 so as to form a slot between it and the front edge of the slabs 9 and into which the bottom edge of the plate glass front plates 17 is stepped. 18 represents the plate glass front top plates, which are supported on the horizontal portions 12 of the frames A, overlapping the top 95 edge of the vertical plates 17, and also extending rearwardly somewhat beyond the portions 12 of the frames A. A triangular metal or wooden filler 19 is mounted on the portions 13 of the frame to aid in supporting 100

the plate 18, and beyond which the plates 18 extend rearwardly overhanging the frames.

The front plates 17 are alined end to end, the open joints coinciding with the frames 5 A which support their ends from within. The top plates 18 abut saugly end to end, their joints also coinciding with the frames A which support their ends from below.

The following is the means provided for 10 clamping adjacent front plates and the top plates in position.

20, Figs. 1, 2 and 9, is a vertically disposed bar of substantially the cross-sectional shape shown in Fig. 9 and provided with lugs 21 near its ends which extend partway rearwardly between the adjacent ends of the front plates 17 and have threaded stems extending through holes in the vertical portions 11 of the frames A. Nuts 22 are screwed up on 25 said stems to snugly clamp the glass plates between bars 20 and the frames. I prefer to interpose felt between glass and metal wherever they impinge, as shown at 23, for the double purpose of making a tight joint and 30 to obviate any danger of cracking the plates under clamping pressure. The upper ends of the bars 20 have outwardly extending platforms 24 which are downwardly notched, as shown in dotted lines at 25 in Fig. 9. 35 26 are angular caps whose horizontal top portions fit down on the abutting corners of the top plates 18 and whose skirts 27 fit down over the front of the platforms 24 of the bars 20. The caps 26 are also provided with depending bosses 28 which fit down into the notches 25, and 29 are screws extending up through holes in the platform 24 and screwed into threaded holes 30 in bosses 28. Thus the plates are clamped in proper position.

40 The ends of the case are formed of plate glass plates 31 whose front vertical edges form right angles with the front plates 17, said angles however being gapped to give clearance for the corner bars. The top plates 45 18 rest upon the tops of the plates 31 and slightly overhang the same at the ends of the case.

The glass plates at the corners of the case are clamped together in the following manner.

50 32 represents a vertically disposed corner bar of triangular cross sectional shape, as shown in Fig. 7, so as to fit over the adjacent edges of the plates 17 and 31. Said bar is 55 provided with rearwardly extending lugs 33 near its ends which are inserted between the edges of the glass plates 17 and 31 and have threaded stems which extend through holes in a wooden back plate 34 which fits in the 60 corner from within. Nuts 35 are then screwed onto said pins, thus clamping the side and front plates together.

The upper end of the bar 32 is provided with a forwardly extending platform 36 provided with a notch 37 in its upper surface.

38 is a cap whose top portion fits down on the corner of the top plate 18 and whose triangular skirt fits down in front of the plates 17 and 31. Said cap is provided with a depending boss 39 which seats in the notch 70 37 and a screw 40 is inserted up through a hole in the floor of said notch and screwed into a threaded hole 42 in said boss.

The caps 26 and 38 have their under faces lined with felt to prevent contact of metal 75 to glass.

The bar 32 has a rearwardly extending bracket 43 provided with a threaded hole in which a screw 44 is engaged. The screw 44 attaches to the bar 32 the front end of a brace 44^a whose rear end is attached as by the screw 44^b to the end of the joist 45. Thus the front corners are properly strengthened.

45 is a wooden or metal joist or molding mounted as by screws on the portions 13 of the frames A and interfitting with the rear edges of the top plates 18. The molding is provided with a felt surface 46 upon which the plates 18 bear. 47 is a second joist or molding, parallel with the molding 45 but mounted at the lower ends of the portions 13 of the frames A. The moldings are provided with bottom flanges 48 upon which are slidably mounted the lower doors B, while the upper doors C are provided with lips 49 which slide on the tops of the moldings. 50 represents filler strips mounted on the frames between the moldings.

The rear wall of the case is preferably of the following construction.

51 is a bottom sill mounted on the floor 1 in the rear of the sill 4, and which is notched to provide clearance for the frames A. 52 is a top bar similarly notched. Vertical posts 53 are provided at suitable intervals, connecting sill 51 and bar 52, and the rectangular spaces defined by the sill, bar and posts are filled with cork or some other heat-insulator material as shown at 54. The sill 51 and the top bar 52 are attached to the frames A, as by screws. 55 is an inclosure of galvanized sheet metal which covers the inner faces of the sills and posts and the insulating material, and which extends over the top of the top bar 51 and extends down on the outside to the bottom edge of the floor 1, thus sealing the insulation against the entrance of moisture. The exterior back wall may be a panel 56.

57 represents wooden or metal lids which are employed to inclose the top of the case in the rear of the sliding doors B and C. If desired the lids may be held in place by screws, 58 represents a board which is fixed in place and extends rearwardly to form a support 125 for a cash register, scales or the like. The front edges of the lids 57 and the board 58 are supported by the lip 59 of the molding 47.

At the ends a wooden closure 60 is provided and in front of the same the vertical 130

5 molding member 61 attached to the end of the top molding 47 and which receives the rear edge of the glass end plate 31. 62 is an inclined molding connecting the top of the ends of the molding 45 and 47 and engaging the inclined top edge of the plate 31.

10 The interior of the case in the rear of the floor slabs 9 forms the refrigerating chamber which may be occupied by the horizontally disposed brine pipes 63 which are shown 15 mounted in a rack 64.

15 Frequently ice and salt are employed as refrigerant. Thus I may place in the rear portion of the case a tank or tanks 65 to contain such refrigerants, the latter being replenished by removing the lids 57. The tanks 20 are removable through said lid openings.

25 Where tanks are employed, the latter should be spaced forwardly from the rear wall of the case to provide for a free circulation of air. To insure the proper positioning of the tanks away from the rear wall I provide the inner surface of the latter with spaced apart and vertically disposed ribs, 66, 30 which may be formed by bending the metal sheet 55 to form the same.

35 It is evident that the interior of my improved case is entirely unobstructed by supports, posts or the like, and thus the articles of food are clearly displayed, and are also within easy reach for removal. The truss-frames which support the superstructure of the case are inconspicuous and rigidly support the superstructure against sagging or 40 vibration.

45 The slabs 9 provide an ornamental and efficient floor upon which the articles to be displayed or their containers may be placed. The method of supporting the floor slabs not only prevents their cracking, but also provides an air space beneath the same which aids in refrigeration.

50 The rear wall and floor of the case are well insulated, so that the contents of the case may be kept at proper temperature at relatively slight expenditure of refrigerant, either in the form of piped brine or contained in tanks.

What I desire to claim is:

55 1. In a display case, the combination of a floor structure including front and rear sills having notches therein, a plurality of spaced apart truss-frames, each of said frames consisting of an integral metallic member comprising vertical portions at front and rear attached at their bases to the floor structure in the notches of said sills and top portions connecting said vertical portions, a front wall mounted against the front vertical portions of said truss-frames, a rear wall mounted against their rear vertical portions, and a top closure supported by their intermediate portions.

60 2. In a display case, the combination of a floor structure including front and rear sills having notches therein, a plurality of spaced

65 apart truss-frames, each of said frames consisting of an integral metallic member comprising vertical portions at front and rear attached at their bases to the floor structure in the notches of said sills and top portions connecting said vertical portions, a front wall 70 comprised of glass plates clamped to the front vertical portions of said truss-frames, a rear wall attached to the rear vertical portions of said truss-frames, and a top closure 75 mounted on the intermediate portions of said truss-frames.

3. In a display case, the combination of a floor structure including front and rear sills having notches therein, a plurality of spaced 80 apart truss-frames, each of said frames consisting of an integral metallic member comprising vertical portions at front and rear attached at their bases to the floor structure in the notches of said sills, and the intermediate 85 top portion of said frames being comprised of horizontal portions and portions inclining rearwardly, top closures supported by said horizontal portions, and sliding closures mounted on said inclined portions, and front 90 and rear walls mounted on the vertical portions.

4. In a display case, the combination of a floor structure including front and rear sills having notches therein, a plurality of spaced 95 apart truss-frames, each of said frames consisting of an integral metallic member comprising vertical portions at front and rear attached at their bases to the floor structure in the notches of said sills, and the intermediate 100 portions of said truss-frames being provided with horizontal portions at the front and rear connected by rearwardly and downwardly inclined portions, top closures mounted on said horizontal portions, and sliding closures mounted on said inclined portions, and front and rear walls attached to said vertical portions.

5. In a display case, the combination of a floor structure including front and rear sills having notches therein, a plurality of spaced 110 apart truss-frames, each of said frames consisting of an integral metallic member comprising vertical portions at front and rear attached at their bases to the floor structure in the notches of said sills, and the intermediate portions of said truss-frames being provided with horizontal portions at the front and rear connected by rearwardly and downwardly inclined portions, glass plates 115 mounted on said front horizontal portions, lids mounted on said rear horizontal portions, and sliding closures mounted on said inclined portions, and front and rear walls attached to said vertical portions.

6. In a display case, the combination of a floor structure including front and rear sills having notches therein, a plurality of spaced 120 apart truss-frames, each of said frames consisting of an integral metallic member com-

prising vertical front and rear portions attached at their bases to the floor structure in the notches of said sills and the intermediate portions of said truss-frames being formed of front horizontal portions, rear horizontal portions and downwardly and rearwardly inclined portions connecting the same, a longitudinally disposed joist connecting said truss-frames at the front ends of said inclined portions, a joist connecting said frames at the rear ends of said inclined portions, front, rear and end walls for said case, glass plates mounted on the front, horizontal portions of said truss-frames, lids mounted on the rear and sliding closures mounted between said joists.

7. In a refrigerator display case, a framing consisting of a floor structure including longitudinally disposed sills at front and rear, a plurality of spaced apart truss-frames, each of said frames comprising an integral metallic member having vertical portions at front and rear whose lower ends are attached to said sills, a horizontal portion extending rearwardly from the front vertical portion, a second horizontal portion extending forwardly from the rear vertical portion, and upwardly inclined portions connecting said horizontal portions, and joists connecting the corresponding ends of the inclined portions of the several frames.

Signed at Pittsburgh, Pa., this 1st day of November, 1928.

JOHN EDWARD GLOEKLER.
